US00D820823S

(12) **United States Design Patent** (10) **Patent No.:** **US D820,823 S**
Ahn (45) **Date of Patent:** **** Jun. 19, 2018**

(54) **MAGNETIC MOUNT FOR ELECTRONIC DEVICE**

(71) Applicant: **Deok Hyun Ahn**, Seoul (KR)

(72) Inventor: **Deok Hyun Ahn**, Seoul (KR)

(73) Assignee: **SPiGEN KOREA CO., LTD.**,
Bongeunsa-ro, Gangnam-gu, Seoul (KR)

(**) Term: **15 Years**

(21) Appl. No.: **29/585,030**

(22) Filed: **Nov. 18, 2016**

(51) LOC (11) Cl. **14-03**

(52) U.S. Cl.

USPC **D14/253**; D13/183

(57) **CLAIM**

The ornamental design for a magnetic mount for an electronic device.

DESCRIPTION

FIG. 1 is a front perspective view of a magnetic mount for an electronic device, showing my new design;

FIG. 2 is a rear perspective view thereof;

FIG. 3 is another front perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof; and,

FIG. 9 is a bottom plan view thereof.

The broken lines illustrate portions of the magnetic mount for an electronic device that form no part of the claimed design.

1 Claim, 9 Drawing Sheets
